ELECTRON TUBE APPARATUS

Richard B. Nelson, Los Altos, Calif., assignor to Varian Associates, San Carlos, Calif., a corporation of California

Original application June 14, 1955, Ser. No. 515,327, now Patent No. 2,944,187, dated July 5, 1960. Divided and this application Aug. 3, 1959, Ser. No. 831,178

8 Claims. (Cl. 315—5)

This invention relates, in general, to electron tube apparatus and, in particular, to novel electron tube apparatus of the type employing cavity resonators such as, for example, high power klystron tubes utilized in systems found in radar, navigation beacons and linear accelerators, etc. The present invention has been divided out of an earlier filed application for Electron Tube Apparatus, Serial No. 515,327, filed June 14, 1955.

In the art of high frequency amplification, for example, that range of frequencies between 2500 and 4000 mc., there has been lacking a pulsed amplifier that would provide high gain, that is, 55 db or over; high power, that is 1 megawatt or more with an average power of 2 kw, at the same time combining reliability and long life (1000 hours) with ease of operation.

Accordingly, it is the object of this invention to provide a novel high power, high gain, electron tube apparatus offering ease of operation, long life, and electrical stability.

One feature of this invention is a novel take-apart joint allowing the joined elements to be separated and then reassembled without the necessity of cleaning the prior adhesive material from the joint thereby preserving the previously acquired alignment.

Another feature of this invention is a novel cathode button support which prevents microphonics and increases thermal efficiency.

A further feature of this invention is a novel system of stiffener plates and strengtheners which maintain proper alignment and rigidity of the apparatus under adverse shock, vibration and temperature conditions thereby materially contributing to stable electrical performance.

Other features and advantages of this invention will become apparent from a perusal of the specifications taken in connection with the accompanying drawings wherein,

Fig. 1 is an elevational view partly in section showing the assembled electron tube apparatus of this invention.

Fig. 2 is a fragmentary side elevation of the structure of Fig. 1.

Fig. 3 is a cross sectional elevational view of the cathode assembly taken along line 3—3 of Fig. 2.

Fig. 4 is a fragmentary view of Fig. 3 showing the cathode take-apart joint.

Fig. 5 is an enlarged fragmentary view of the novel cathode button support.

Fig. 6 is an enlarged part sectional view taken along line 6—6 of Fig. 2 looking in the direction of the arrows, and

Fig. 7 is a sectional view taken along line 7—7 of Fig. 2 looking in the direction of the arrows.

The construction of the novel electron tube apparatus will now be described followed by a description of the operation and function of the apparatus.

Referring now to Fig. 1, the novel tube apparatus comprises a cathode structure 1, resonators 2, 3, 4 and 5 and a collector assembly 6. Signal energy to be amplified is

2

supplied to the first resonator 2 via a concentric line input 7 and amplified in successive resonators 3 and 4. The amplified signal is extracted from the output resonator 5 and propagated to the load through waveguide 8. The cathode is immersed in an oil bath contained within a tank 9 to prevent arc-overs in the external cathode region. Surrounding the resonators is an electrical coil 11 for creating a strong magnetic field to confine the electron beam in the resonator region.

Referring now to Fig. 3, a source of electrons is supported from and contained within an evacuated cathode envelope 12. Comprising the cathode envelope are a plurality of tubular segments 13, 14, 15, 16, 17, 18, 19, 21 and 22 joined together at their ends. Of these tubular segments 16, 19 and 22 are of good insulating material as of glass to allow independent operating potentials to be applied to certain portions of the cathode assembly. Tubular segments 13 and 14 are made of materials having a high magnetic permeability as of steel to provide shielding of the cathode from magnetic fields in the cathode vicinity. The cathode envelope is closed at its lower end by a bottom cup 23 and at its upward end is securely held by pole piece 24.

To allow the cathode assembly to be replaced a novel take-apart joint between cathode envelope segments 13 and 14 is provided (see Fig. 4). At the joint, proper longitudinal alignment of the lower cathode structure is obtained through the upper horizontal interface. Correct transverse alignment of the cathode is obtained through the vertical interface. Interposed between these two interfaces is an area of mutually opposing surfaces which are noncontacting, that is, the opposing faces are spaced apart. These surfaces are spaced apart to create a void which destroys the capillary action tending to draw the adhesive substance 25 from its applied region through the horizontal interface and onto the vertical interface. If the void is not provided adhesive material will contaminate a greater portion of the interfaces. When the lower cathode assembly is then to be replaced, the adhesive material sticking to the aligning surfaces must be removed. Oftentimes in cleaning the adhesive from these surfaces the previously acquired alignment is destroyed. The present novel joint design allows the cathode to be removed, worked on and replaced without expending unnecessary time in cleaning the joint, meanwhile preserving the previously acquired proper transverse alignment.

Encircling the cathode envelope at segment 17 and fixedly secured thereto is a novel annular cathode flange 26. The cathode flange is of heavier construction and serves to strengthen the more fragile cathode envelope. Furthermore cathode flange 26 serves as a bumper protector for the glass insulator 16.

The internal cathode structure is shown in detail in Fig. 3. Contained within the cathode envelope 12 is preferably a concave cathode emitter 35 having an annular focus ring 36 positioned slightly in front of said button and carried by a tubular focus shield 37 which in turn is supported from the cathode envelope by focus shield support 38. Fixedly secured to the cathode focusing ring 36 and extending downwardly therefrom is a novel tubular cathode emitter support 39 (see Fig. 5) having slots running longitudinally thereof thereby creating a plurality of fingers 41. Also carried by the focus shield 37 is an annular double partition heat shield 42 (Fig. 3).

The present novel cathode construction features a cathode emitter surrounded by a plurality of partitions all serving to retain the heat energy within the cathode emitter region thereby substantially increasing thermal efficiency. The cathode emitter support 39 is particularly unique in that the longitudinal slots serve to inhibit heat

conduction while the finger portions 41 reflect the heat energy back to the cathode emitter. It has been found that certain fingers may be cut out to aid in evacuation of the inner cathode regions without substantially impairing thermal efficiency. A second embodiment of the novel cathode emitter support 39 has certain fingers bent outwardly a short distance to substantially a condition of constant diameter for those portions of the tubular member, leaving a plurality of convergent fingers. This novel design further prevents heat loss by conduction since fewer fingers make contact with the cathode emitter. In all embodiments the cathode emitter 35 is rigidly secured to the extremities of certain of the button support fingers.

Heating the cathode emitter 35, a double spiral wound filament 43 is supported upon three support rods, longer heater lead 44, short heater lead 45 and center support 46. Since center support 46 carries no current it is insulated electrically from the heater filament 43 through insulator 47. Extending into the insulator and connecting directly to the filament, is heater support 48. Providing base supports for short heater lead 45 and filament center support 46 are two circular plates, heater support flange 49 and getter flange 51 respectively, said flanges being rigidly secured to the cathode envelope 12. Long heater lead 44 extends downwardly through noncontacting openings in heater support flange 49 and getter flange 51 and anchors on bottom cup 23.

Referring now to Figs. 2 and 6, a plurality of re-entrant type cavity resonators 2, 3, 4 and 5 are spaced along thick-walled cylindrical drift tubes 52. Spiraling around the drift tubes is a cooling coil 53 through which is circulated a coolant to carry away heat generated in the drift tube vicinity. Encircling and securely affixed to the drift tube substantially at either end thereof are two magnetic pole pieces, cathode pole piece 24 and anode pole piece 54. A plurality of stiffener plates 55 likewise encircle the drift tube and are spaced apart in the drift tube midsection. Interconnecting the pole pieces and stiffener plates are a plurality of stiffener rods 56 which are rigidly secured to the stiffener plates as by brazing. It has been found that by utilization of the novel stiffener plates and rods the microphonic tendency of such an electron tube apparatus was substantially reduced. Moreover, electrical stability under high ambient temperatures was greatly enhanced. Because of the magnetic focusing, not yet fully described, the aforementioned magnetic pole pieces 24 and 54 are constructed of a material of high magnetic permeability such as, for example, iron. On the other hand, in the area between the pole pieces the magnetic field should not be perturbed, thus where possible parts should be made of materials possessing no magnetism, for example, the stiffener rods 56 and plates 55 could be constructed of a non-magnetic variety of stainless steel.

In operation electrons are emitted from the cathode focused into a beam by the focusing electrode 36 and accelerated through the drift tube. The signal to be amplified is fed into the input cavity 2 where the beam is velocity modulated. As the modulated beam travels down the drift tube it is further modulated by the intermediate bunching cavities 3 and 4, while within the drift tube the beam is confined in diameter against forces tending to spread the beam, such as space charge forces, by the magnetic field lines supplied by the focusing coils 11, said lines of flux being parallel to the drift tube in this region. The output cavity extracts electromagnetic energy from the modulated beam and said energy is then coupled out of the output cavity through iris 74 (see Fig. 7) and propagated through waveguide 8 and window 75 to the load. Tuning of the tube is obtained by a movable wall type tuning plunger which is movable within the resonator by rotation of a worm shaft, not shown, which operates upon actuating rod 66 which in turn cooperates through pinion 65 to cause tuner rack support and attached plunger and diaphragm to move in and out of the

cavity thereby changing the resonant frequency of said cavity.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

10 This application is a division of U.S. application, Serial No. 515,327, filed June 14, 1955, now U.S. Patent No. 2,944,187.

What is claimed is:

1. In an electron tube apparatus a vacuum tight take-apart joint comprising two tubular segments of the cathode envelope having a pair of mutually opposing surfaces and adapted to be sealed together via the intermediary of a sealing material, certain portions of said opposing surfaces forming a longitudinal aligning interface, certain other portions of said opposing surfaces at right angles to said longitudinal aligning interface forming a transverse aligning interface, and portions of said opposing surfaces disposed between said longitudinal and said transverse aligning interfaces spaced apart to create a void therebetween to prevent contamination of the aligning surfaces by sealing material.

2. In an electron tube apparatus a cathode emitter support comprising a tubular support having slots at one end running longitudinally therein forming a plurality of fingers, and only certain of said fingers converging inwardly and physically coupled and electrically conductively connected to the cathode emitter thereby rigidly supporting the emitter in a substantially microphonic free manner.

3. In an electron tube apparatus a cathode emitter support comprising a tubular support slotted such as to form a plurality of fingers, and certain of said fingers physically coupled and electrically conductively connected to the cathode emitter, and the cathode emitter supported from said fingers in enveloping relationship whereby the emitter is substantially contained within said tubular support thereby minimizing the escape of radiant heat energy and serving to retain the energy within the vicinity of the cathode emitter thereby increasing the emission efficiency in use.

4. In an electron tube apparatus utilizing the interaction of a high frequency electromagnetic field with a pencil-like beam of electrons passable therethrough, an elongated rigid tubular vacuum envelope containing the beam-field interaction spaces therewithin, strengthening

50 plate means disposed transversely of and rigidly coupled to said elongated tubular envelope, and strengthening rod means rigidly coupled to said strengthening plate means and running longitudinally of said rigid elongated envelope to provide a rigid integral structure thereby minimizing unwanted microphonics and preventing shock and vibrational distortions of the electron tube apparatus.

5. In an apparatus as claimed in claim 4 wherein said elongated rigid tubular vacuum envelope comprises a thick-walled tubular segment forming the drift tube portion of the electron tube apparatus, a tubular segment of thinner wall construction than said drift tube segment forming a cavity resonator portion for containing the electromagnetic fields of the tube apparatus in use, and wherein in said strengthening plate means are carried upon said thick-walled drift tube segments whereby the relatively large mass of the drift tube segments is rigidly supported to thereby prevent unwanted microphonics in vibrational environments.

6. In an apparatus as claimed in claim 5 wherein said strengthening rods and said strengthening plates are made of a non-magnetic material.

7. The apparatus according to claim 3 wherein the cathode emitter includes a tubular member portion having a first and second end portion and being closed at

said first end portion by a wall having a concave surface forming an electron emitting surface of the emitter, said emitter support fingers having free end portions, and said tubular member portion of the cathode emitter and said emitter support fingers being fixedly physically and electrically connected together at the free ends of said certain emitter support fingers and substantially at the second end of said tubular cathode member for minimiz-

ing conduction of thermal energy from said cathode emitter in use.

8. The apparatus according to claim 7 wherein certain other of said support fingers have their free end portions spaced apart from said second end portion of said tubular cathode emitter member portion.
